UNITED STATES PATENT OFFICE

CHARLES C. FLYNN, OF DETROIT, MICHIGAN

SOUND AMPLIFIER

Application filed March 19, 1928. Serial No. 262,616.

My invention relates to a new and useful improvement in a sound amplifier or sounding chamber intended for various uses where a sound amplifying device is required, such as sound chambers of phonographs, loud speakers on radios, etc.

It is an object of the present invention to provide sound amplifying device of this kind in which reflecting surfaces of the device are arranged and curved to provide surfaces determining harmonic curves, to the end that the natural oscillations in the sound waves may not be interfered with, but may be increased and amplified to produce the desired amplification in the device.

It is another object of the invention to provide a device of this kind which will be simple in structure, economical of manufacture and highly efficient in use.

Another object of the invention is the provision of passages through which the sound must pass before emanating from the amplifying device and forming these passages with surfaces designed to amplify the sounds passing therethrough.

Other objects will appear hereinafter.

The invention consists in the combination and arrangement of parts hereinafter described and claimed.

The invention will be best understood from a reference to the accompanying drawings which form a part of this specification and in which,

Fig. 1 is a longitudinal central sectional view of the invention.

Fig. 2 is a sectional view taken on line 2-2 of Fig. 1.

Fig. 3 is a sectional view taken on line 3-3 of Fig. 1.

Fig. 4 is a fragmentary sectional view taken on line 4-4 of Fig. 3.

The device as set out herein has proven from experience to be most efficient in amplifying and it has been attempted to construct the device along certain well defined mathematical lines based on the conception that sound is in the form of wave motion and that the vibrations or oscillations are in line with the direction of propagation of the sound, and that these vibrations or oscillations are in

reality the result of the impact of the particles or molecules of the medium of propagation due to the elasticity of these particles. It is believed that the motion from a state of rest or a change in direction, or change in frequency of oscillations along the direction of propagation, is due to the application of a force or forces to the molecular structure of the medium of propagation, this molecular impact transmitting motion or vibration from the initial point of application to the ultimate end, the medium itself not being moved bodily but transmitting the motion from molecule to molecule.

To increase these oscillations or vibrations by reflection or refraction by the addition of resultant reflected or refracted oscillations along the axis of motion, is one of the objects of the invention, and this is accomplished by determining the profile of the various curves in the sound passages, so that these curves are harmonic in nature.

In the sound passages two sides are designed to be parallel and two sides curved, the curve being a harmonic one, and the curved sides terminating in parallel sides at the same point that the parallel sides begin to curve.

A head 7 which is designed for attachment to the conduit which leads from the sound producer, is attached by suitable screws 8 to the passage-forming walls 9 and 10 and the wedges 13 and 14. The inner surface of these walls 9 and 10 are parallel for a portion of their distance as at 11, and are flaring outwardly at the portion 12, this curve being a harmonic one.

The inner surface of the wedge members 13 and 14 are inclined and their inclination terminates at the point where the surface 12 begins to curve outwardly.

The housing comprises side walls 15 and 16 which are made preferably of resonant material, such as wood, and secured to the inner surface of each of these walls at the central portion thereof are the securing plates 17 and 18 which are formed preferably heart-shaped, as appears in Fig. 1.

Hollow units are provided for positioning at opposite sides of the members 9 and 10,

as shown clearly in Figs. 1 and 2, these units comprising the side walls 19 and 20, which engage against the inner surfaces of the securing plates 18 and 17.

Connecting these side walls 19 and 20 is the transversely extended wall 21 which is adapted to engage against the sides of the members 9 and 10, so that sound passing inwardly between these members 9 and 10 is not permitted to escape except around the ends of these members, the ends of these members being curved, as clearly appears in Fig. 3.

Engaging the outer edges of the side walls 19 and 20 and the upper and lower edges of the wall 21, so as to enclose this unit and form a closed hollow unit, is a diaphragm or closure 22 preferably made from paper or other similar material.

A similar unit is mounted at the opposite side of the members 9 and 10 and comprises the side walls 19' and 20', the transversely extended wall 21' and the covering 22'.

Engaging the outer edges of the side walls 15 and 16 so as to form with these side walls a housing is a covering or diaphragm 23 preferably made from paper or the like.

Connecting the side walls 15 and 16 at their lower edges adjacent their ends are the rails 24 and 25 which also serve as a support for a suitable closure or screen 26 which may or may not be used, as desired.

Engaging at its opposite ends the inner surface of the plates 17 and 18, adjacent their lower ends, is the reflecting plate 27 which is formed on its inner surface with recesses 28 and 29, these recesses having a surface which is curved, the curve being a harmonic one. The surfaces of these recesses 28 and 29 meet at a point which is central between the members 9 and 10.

In use the sound is transmitted into the head 7 and thence inwardly of the housing between the members 9 and 10, the inclined surface of the wedge members permitting a diverging of the sound waves, these sound waves engaging the surface 12, passing inwardly and thence around the curved ends of the members 9 and 10, and reflecting from the curved surfaces of the recesses 28 and 29, and thence backwardly so that the surfaces 30 and 31, which are also curved slightly at a harmonic curve, will serve as a reflecting body. The sound then travels to the right or left of the device shown in over the top of the plates 21 or 21' into the space 33 or 33'.

In this regard, it will be noted that the inner surface of the covering 23, at opposite sides of the transverse medial line of the main housing, is also curved at a harmonic curve and the covers 22 and 22' are also curved at a harmonic curve to afford the reflecting surface 34 which cooperates with the surface 33.

In this way the sound, after being con-

ducted into the amplifier, is always travelling in contact with and being reflected and turned by surfaces which are curved harmonically.

Thus the surfaces serve to, instead of interfering with the vibrations and oscillations in the sound waves, intensify and amplify these vibrations with the desired increase in volume of sound.

In each passageway at least two of these sides forming the passageway are parallel and the other two sides curved on a harmonic curve. It will also be noted that these passageways in which the sound travels is substantially a continuation of the passage leading thereto, each succeeding passage increasing harmonically across two sides. In other words, each succeeding passage has a cross section width such that it increases harmonically from the start of the first section before the sound reaches the recesses 28 and 29 and continues until the sound is transmitted from the chambers 33 and 33'. The two final openings which are the ends of the chambers 33 and 33' are provided with a view to producing the sensation of depth or space not obtainable by a single horn or device.

In this amplifying device there are provided a pair of cooperating sound transmitters or amplifiers, receiving the sounds from the same source, and constructed on their inner or reflecting surface harmonically.

While I have illustrated and described the preferred form of my invention, I do not wish to limit myself to the precise details of structure shown, but desire to avail myself of such variations and modifications as come within the scope of the appended claims.

Having thus described my invention, what I claim as new and desire to secure by Letters Patent is:

1. A device of the class described, comprising: a housing; a pair of passage forming oppositely disposed walls spaced apart; a pair of oppositely disposed wedges co-operating with said walls and enclosing a passage, the inner surfaces of said wedges being inclined to their longitudinal axis, the inner surfaces of said wall forming members throughout the major portion of said wedges being parallel and throughout the rest of their length being flared outwardly from each other on harmonic curves.

2. A device of the class described, comprising: a housing; a pair of passage forming oppositely disposed walls spaced apart; a pair of oppositely disposed wedges co-operating with said walls and enclosing a passage, the inner surfaces of said wedges being inclined to their longitudinal axis, the inner surfaces of said wall forming members throughout the major portion of said wedges being parallel and throughout the rest of their length being flared outwardly from each other on harmonic curves; a reflecting plate positioned adjacent the ends of said

wall forming members in spaced relation thereto and extended across the passage formed thereby and provided at opposite sides of the longitudinal medial line of said 5 passage with curved recesses, the curve of said recesses being harmonic.

3. A device of the class described, comprising: a housing having side walls in spaced relation; a covering engaging the 10 edges of said side walls on all sides except one and enclosing the space between said side walls; securing plates mounted on the inner surface of said side walls; a reflecting plate joining said securing plates adjacent the 15 open side of said housing; a pair of hollow members projecting inwardly of said housing and engaging adjacent their outer ends the sides of said reflecting plate; and passage forming members projected through one side 20 of said housing and extending inwardly between said hollow members and forming a sound passage between the same terminating adjacent said reflecting plate.

4. A device of the class described, comprising: a housing having side walls in spaced relation; a covering engaging the 25 edges of said side walls on all sides except one and enclosing the space between said side walls; securing plates mounted on the inner 30 surface of said side walls; a reflecting plate joining said securing plates adjacent the open side of said housing; a pair of hollow members projecting inwardly of said housing and engaging adjacent their outer ends 35 the sides of said reflecting plate; and passage forming members projected through one side of said housing and extending inwardly between said hollow members and forming a sound passage between the same terminating 40 adjacent said reflecting plate, said reflecting plate having at opposite sides of the medial line of said passage grooved recesses formed therein.

In testimony whereof I have signed the
45 foregoing specification.

CHARLES C. FLYNN.
